WALTER L. GRAUL AND REGINALD H. TOWLER, OF DETROIT, MICHIGAN.

DISCHARGING PLATFORM FOR COKE OVENS.

Application filed March 19, 1920. Serial No. 367,072.

To all whom it may concern:

Be it known that we, WALTER L. GRAUL and REGINALD H. TOWLER, citizens of the United States, residing at Detroit, in the 5 county of Wayne and State of Michigan, have invented a new and Improved Discharging Platform for Coke Ovens, of which the following is a specification.

Our invention relates to the platform extending along the discharge side of a block 10 of coke ovens across which the coke passes when discharged from the ovens. Heretofore such platforms have been disposed horizontally in order to provide means of access to the discharge end of the ovens and the coke 15 in being pushed from the ovens has been pushed across the platform and then dropped horizontally into a receiving car, a considerable amount of hot coke being thus left 20 on the platform and required to be afterward shoveled off.

The object of our improvements is to provide a self discharging platform and at the same time provide a safe and convenient 25 means of access for the workmen to the discharge end of the ovens.

To this end our invention consists in providing a discharge platform which extends along the discharge side of a block of 30 ovens and is inclined downwardly therefrom and in combination with this a horizontally disposed platform by which access to the ovens can be had, the parts of which immediately in front of each oven are arranged to be removable so as not to interfere 35 with the discharge of coke from the ovens.

The invention will be best understood from the accompanying drawings, illustrating 40 an embodiment thereof, Fig. 1 of which shows a front elevation of the device, Fig. 2 shows a section on the line 2—2 Fig. 1, Fig. 3 shows details on an enlarged scale of the railing of the horizontal platform or path 45 and Fig. 4 shows details of the pivotal support of the movable sections of the horizontal platform. Referring to the drawings, A, indicates the discharge end of a series, or 50 block of coke ovens, to which is secured the downwardly inclined discharge platform, B, which runs along the ovens immediately below the discharge oven doors and is upheld by suitable supports as, b.

Along the face of the ovens, A, above the 55 discharge platform, B, extends a horizontally disposed platform or path, C. The

platform, C, is composed of sections, D, having suitable supports as, d, which are located in front of the spaces between the discharge openings, E, of the ovens, and are fixed in position, and of movable sections, F, which lie between the fixed sections, D, and are in this case rotatably mounted, as on suitably supported axes, f. The space between each two of the fixed path sections, D, is occupied by two of the movable sections, F, which span the space in front of one of the discharge openings, E, of the ovens. Each of the movable sections, F, is provided with a hand rail, G, provided with suitable supports, g, so placed that when the path sections, F, in front of an oven opening are turned back to permit the discharge of the oven their rails, G, with their supports will pass by the rails of the adjacent path sections on each side as shown in Figs. 1 and 3.

The path sections, F, when in position in front of the discharge openings of the ovens are suitably supported as by means of a 80 supporting foot, H, secured to one of the sections and having its lower end adapted to engage in a socket, h, in the platform, B, while the edge of the other section rests on the one thus supported. Other means of 85 supporting the section, F, which will readily occur to those skilled in the art, may, however, be employed.

When the path sections, F, are all in their horizontal position they, together with the 90 path sections, D, provide a continuous path along the oven block thus giving the workmen safe and easy access thereto.

When it is required to discharge the coke from an oven the path sections, F, F, with 95 their rails and supports, lying in front of such oven are turned back as shown in the central portion of Fig. 1, and the coke is pushed in the usual manner. The discharged coke passes freely down the inclined discharge platform, B, and into the desired receptacle, as a quenching car, indicated at, I, without leaving any material quantity of hot débris. The removed sections, F, are then replaced in their horizontal position 100 and the path is ready for use as before.

Having thus described our invention what we claim as new and desire to secure by Letters Patent is:—

1. The combination with a block of coke 110 ovens of a discharge platform extending along the discharge ends of the ovens con-

sisting of a platform inclined downwardly from the oven wall and a horizontal platform adjoining the oven wall and extending along the oven block above the inclined platform (and supported thereby) and having the portions thereof opposite the oven openings removable so as to give free access from the oven openings to the inclined platform.

2. The combination with a block of coke 10 ovens of a discharge platform extending along the discharge ends of the ovens consisting of a platform inclined downwardly from the oven wall and a railed horizontal

platform adjoining the oven wall and extending along the oven block above the inclined 15 platform, and having the portions thereof opposite the oven openings removable so as to give free access from the oven openings to the inclined platform said removable portions being supported at their free end by a 20 pivoted member resting in a seat on the inclined platform.

In testimony whereof we have affixed our signatures, this 26th day of February 1920.

WALTER L. GRAUL.

REGINALD H. TOWLER.
